BENDING BRAKE

Peter Kilham, Attleboro, Mass.

Continuation of application Serial No. 451,001,
 July 15, 1942. This application September 9,
 1944, Serial No. 553,322

22 Claims. (Cl. 153—16)

1

My invention relates to an improvement in brakes for bending sheet metals and the like.

One purpose is the provision of an adaptable brake which may be readily adjusted for the bending of relatively small pieces of various size and shape, especially those such as tempered aluminum, requiring a radius bend.

Another purpose is the provision of an adaptable hand operated brake which may be operated by a single operator.

Another purpose is the provision of an improved means for directing the pressure against the work.

Other purposes will appear from time to time in the course of the specification and claims.

This application is a continuation of my application for Bending brake, Serial Number 451,001 filed July 15, 1942 and subsequently abandoned.

I illustrate my invention more or less diagrammatically in the accompanying drawings wherein:

Figure 1 is a perspective;

Figure 2 is a section on an enlarged scale on the line 2—2 of Figure 1;

Figure 3 is a plan view;

Figure 4 is a section on the line 4—4 of Figure 1;

Figure 5 is a section on the line 5—5 of Figure 2;

Figure 6 is a section on the line 6—6 of Figure 3;

Figure 7 is a partial view similar to Figure 6, with the parts in a different position;

Figure 8 is a section on the line 8—8 of Figure 3;

Figure 9 is a perspective illustrating a different adjustment;

Figure 10 is a section on the line 10—10 of Figure 9; and

Figure 11 is a partial perspective of a further different adjustment.

Like parts are indicated by like symbols throughout the specification and drawings.

Referring to the drawings, I generally indicate any suitable base, upstanding from which extends the support 2. At the upper end of the support is mounted any suitable top plate 3, having downwardly extending side flanges 4, formed, as shown in Figure 8, by angle members. It will be understood that the portion 3, 4 may be made in a single piece if desired. 5 illustrates a top plate, or a pair of top plates, separated by a channel 6. It will be understood that this also

2

may, if desired, be made integral with the member 3, 4.

Received in the channel 6 is a guide strip 7, which carries at its forward end a stop bar 8, which is adapted to rest flush against the top of the plates 5 and slide forwardly and backwardly therealong, guided by the member 7. Mounted on the top of the stop bar 8 is an adjusting bar 9, to which additional stop members 11 may be secured, as by insertion between the members 8 and 9 and tightening up of the screws 10.

It will be understood that the bar itself may be employed as a stop member, or that these additional stop members 11 may be inserted.

15 They may be formed for example of sheet metal, with a downwardly bent forward edge 12, as indicated in Figure 2. A plurality of them may be simultaneously employed, and their forward extension may be simultaneously varied, so that a piece having a number of bends may be gauged and bent at a number of stations without delaying the work to make stop adjustments, and so that a piece with an irregular contour can be accommodated.

20 In order to clamp the gauge structure, I provide a clamping block 14, which is held for example by a bolt 15 to one of the members 5, and extends across the bar or guide piece 7. It will be noted that the top of the bar 7 is slightly 25 higher than the top of the members 5. Thus, when the locking or clamping bar 14 is moved down, it performs a clamping function. It may be controlled by any suitable hand screw 16.

In order to clamp the work on the brake, I 30 provide a clamp structure including the frame element generally indicated as A, having a rear bar or element 20 and forwardly extending converging elements or bars 21, which converge centrally and forwardly, as at 22, and terminate in 35 a head 23, herein shown as welded thereto, and having an upwardly and outwardly extending flange 24, and a downwardly inclined plane forward face 25.

It will be understood that any suitable bending or gripping element 26 may be screwed or bolted to the head 23, as shown for example in Figures 6 and 7. I illustrate for example a pair of bolts 27. It will be understood that a wide variety of shape and size of plates may be employed. I illustrate for example in Figure 1 a plate 26a having laterally extending relatively thin arms 26b. In Figure 11, I illustrate a much narrower plate 26c having no such arms. It will be realized that the bending plate may be varied 50 to suit the work. Where a relatively narrow

piece is to be bent, or a piece having side flanges, as shown in Figure 11, the narrow blade is employed. Where it is desired to grip a wide piece, as in Figure 1, a wide blade is mounted. Special blades will be useful in making short square tubes and other special shapes. Also, the forward edge of the blade, around which the piece is bent, may be rounded, thus giving a radius bend, which is required in certain materials, notably tempered aluminum, which are too brittle to be bent sharply.

The structure thus formed is pivoted at the rear edge as follows: Sockets 30 (see Fig. 3) receive pins 31 on the blocks 32, having outwardly extending relatively narrow portions 33 (see Fig. 2) conforming to generally horizontal slots 34 in the upwardly extending brackets 35, which are secured to the side of the brake, for example by bolts or screws 36. It will be understood that if desired, the pins 31 and the bore 30 may be made continuous, so that the pressure frame or blade carrying support is pivoted upon a continuous rod extending through the device.

37 is a manually controlled screw for varying the position of the blocks against the compression of the springs 38. It is thus apparent that the forward edge of the gripping member or plate 26 can be adjusted toward or away from the front edge of the working plate, depending, for example, on the thickness of the metal to be bent.

39 is any suitable tool or spare part compartment which may for convenience be mounted at the rear of the brake.

In order to urge the brake or clamp into material gripping position, I provide the following structure: 40 (see Fig. 8) indicates a bracket depending from one of the flanges 4, having a horizontal offset portion 41, apertured to receive a screw 42, which is unitary with a generally vertical supporting bar 43, to the upper end of which, as at 44, is pivoted the pressure bar 45, which extends transversely and generally horizontally across the top of the device.

46 is a spring which normally thrusts the bar 43 up as far as the flange 41 of the hand wheel 48 will permit. Thus, the bar 43 and the pivot 44 can be vertically adjusted.

49 is any suitable retaining means for maintaining the vertical alignment of the bar 43 and forms part of an adjustment which will later be described.

As shown for example in Figure 8, it will be observed that the pressure bar 45 is connected by a spring 50 with a forward portion of one of the clamp arms 21. The clamp arms 21 are also connected adjacent their forward ends by a species of upwardly arched bridge 51, the upper portion of which serves as a contact between the clamp structure and the pressure bar 45. It will be observed that a rocking contact is provided at 51, during relative movement of the parts, and that the area of contact as shown in Figure 8, is relatively small, is remote from the axis of the clamping structure as a whole, and is aligned with the center of the top of the brake.

The opposite end of the bar 45 has pivoted thereto, as at 52, a pair of links 53, which in turn are pivoted, as at 54, to a lever 55, the outer end of which terminates in an operating knob 56, and the inner end of which is pivoted, as at 57, to the bracket 58, secured to the side of the brake. The dotted line position in Figure 8 illustrates the release position, and the full line the pressure applying position. It will be observed that in

the locking position the center 54 passes beyond dead center in relation to the centers 52 and 57, and the device thus is kept locked, independent of the maintenance of pressure on the lever 55.

5 In other words, the device is self-locking when it passes beyond dead center.

Extending downwardly from the lever 55 is a pair of links 60, pivoted to the lever 55, as at 61, and pivoted, as at 62, to a vertically guided bar 63, which terminates in a species of stirrup 64, having a bottom transverse element 65. 66 is a treadle, pivoted as at 67, to the base 1 at a point intermediate the ends of the treadle. The forward end of the treadle terminates in a heel-engaging element 68. The rear end of the treadle is provided with a loop 69 (see Fig. 4), or any other suitable means for engaging the cross piece 65 of the stirrup 64. It will be understood, therefore, that when the user presses down with the toe of his foot on the left part of the treadle 66, referring to the position of parts shown in Figure 4, the bar 63, and thus the lever 55, is moved towards locking position. On the other hand, if the user presses down with his heel on the right arm of the treadle, referring to the position of parts in Fig. 4, the bar 63 is kicked up and thus the lever 55 is moved to the release position, and the pressure bar 45 is released.

After the release movement of 55 has been initiated, and the center 54 moves to the release side of the plane defined by the centers 52 and 57, the arm 10, with its spring 71, is effective to move or tend to move the lever 55 further towards release position, without additional lifting movement by the foot of the user. The tension of the spring 71 may be raised by means of the eye bolt 71a mounted in a bracket 71b on the support 2, and an adjusting nut 71c.

There is a rolling or free connection between 40 the outer end of the lever 70 and the links 60 obtained by a cross pin 72, seated in a bent depressed portion 73 at the end of the lever 70. Any suitable guides may be employed for the bar 63. I illustrate for example a pair of brackets 74, 75, and a vertical guide piece 76 secured thereto.

Assuming that the properly gauged sheet of metal to be bent is gripped between the member 26 and the forward edge of the members 5, the actual bend is applied by the lift blade 80. The lift blade is secured by any suitable screws 81 to an adjusting and supporting plate 82, illustrated for example in Figure 9, which shows the lift blade removed.

Formed for convenience unitarily with the plate 82 are end elements 83, which extend upwardly to form hubs or bearing members 84, within which are any suitable bearings, herein shown as anti-friction bearing means 85 (see Fig. 5), the inner race of which surrounds a pin 86, which is fixed in a bracket 87, which is adjustable about a horizontal axis defined for example by the screw 88. As shown in Figure 2, the bracket has an elongated aperture 89, through which passes the adjusting screw 90, and an upper portion of the bracket is engaged by a set screw 91, the position of which is controlled by a lock nut 92. Each screw 91 passes through one of the side blocks 93, one of which carries the above mentioned guide 49 (see Fig. 3).

It will be thus observed that the center of rotation of the lift blade can be adjusted in relation to the forward edge of the structure. With the parts as adjusted in Figure 2, the center of rotation of the lift blade is located slightly above

and slightly forwardly of the edge of the work receiving top of the brake.

The lift blade 80 may be slightly vertically adjusted on the support 82, the screws 81 passing through slight slots 81a in the blade 80. The final adjustment is made for example by the set screw 95, shown in Figure 2 with its lock nut 96, the screw passing through the projection 97 extending outwardly from the side element 83 of the member 82.

As shown in Figure 9, the lift blade 80 has been removed, and a substitute lift element or bending tool 98 has been positioned, being held by an upper guiding block 99 secured thereto, and engaging the top of the bar 82, and a locking screw 100 (see Fig. 10) passing through one of the horizontal adjusting slots 101, of which for convenience two are shown. It will be understood that a plurality of tools 98 may be applied at the same time. They may be applied for bending small portions or for bending parts of large pieces where ears are bent, or for bending a center portion of a piece only.

The lift structure is manually actuated by the handle 103, the ends of the handle being secured in any suitable fashion to the bar 82. The user simply lifts forwardly and upwardly on the member 103 and bends the work. The upward limit of the bending movement is controlled by the limit rod 104, which is pivoted as at 105 to ears extending outwardly from the rear face of the bar 82. It slides through a pivoted block 106, pivoted on the downwardly extending bracket or yoke 107, connected to the front of the brake base. An adjustable limit element 108 may be held at any desired adjustment on rod 104, for example by the screw 109, thus limiting the upper bending movement of the lift 98.

It will be realized that whereas I have described and illustrated a practical and operative device, nevertheless many changes may be made in the size, shape, number and disposition of parts without departing from the spirit of my invention.

I therefore wish my drawings and description to be taken as in a broad sense illustrative or diagrammatic, rather than as a limitation to my precise showing.

The use and operation of my invention are as follows:

I provide a small, light, adaptable, and yet powerful bending brake which is adapted for one man operation and which can be quickly reset to take pieces of a substantial variety of sizes and shapes and angular requirement. In the first place, I provide what is in effect a three-point contact for the braking frame, centering the downward thrust at the forward end of a triangle formed by the members 20 and 21, which entirely avoids the customarily employed means of separate application of force at the opposite ends of a brake blade. The actual thrust is delivered centrally to the above mentioned triangle by the contact between the transverse clamp bar 45 and the convex top of the bridge 51. I provide a series of adjustments which permit my device to be adapted for use with varying gauges of material and material of varying resistance to bending.

Thus, the pivot 44 of the bar 45 can be upwardly adjusted, the frame 20, 21 can be longitudinally and horizontally adjusted, the pivot point of the lift blade is adjustable by rotation of the bar 87 about the center 88, the lift blade 80 is vertically adjustable on its support, the lifting movement is adjustable by controlling the position of the stop 108, thus varying or adjusting the angle of the bend.

The material is readily and adjustably gauged by moving the gauge bar 8 backward or forward on the working surface. I find it highly advantageous to associate with the gauge bar 8 additional gauges 11, which may be used in a wide variety of sizes, shapes and numbers, and which can be themselves adjusted forwardly and rearwardly in relation to the bar 8, and can have their forward faces either parallel with or not parallel with the front face of the gauge bar 8. Thus, parts of varying size and varying shape can be handled or parts with irregular rear edges can readily be gauged for bending, or parts with a number of bends can be bent at stations transversely across the working edge of the machine without delaying work for adjustment.

The clamp blade proper 26 can be removed and adjusted and widely varied in form, as seen for example by a comparison between Figures 1 and 11. The lift blade 80 can not only be adjusted but can be entirely removed and replaced by other individual lift elements, which may be used singly or multiply, and can be longitudinally adjusted along the bar 82, as shown in Figure 9.

In using the device the operator can employ the ball 56 as a handle for manual operation, or he can to a substantial degree employ foot operation by employing the treadle 66.

The clamping mechanism may be actuated to move the center 54 beyond dead center in relation to the centers 52 and 57, which can be done either by hand or by foot pressure. Or the user can maintain a constant foot pressure and not move the center 54 beyond dead center. In that case, a light upward movement of the foot is sufficient to release the work. Thus, I provide a highly flexible structure, which can handle with great ease and speed a maximum of different forms of parts to be bent, and can make a radius bend such as is required in tempered aluminum.

I claim:

1. In a bending and forming brake, a stationary bed, clamping means mounted above said bed for clamping the work downwardly thereagainst, and a bending element pivoted adjacent the forward edge of the bed, and means for adjusting the axis of rotation of said bending element in relation to the forward upper edge of the bed, including a pair of arms located adjustably one at each side of a front portion of the bed, a pivotal connection between each said arm and the bending element, and means for adjusting each said arm in relation to said bed.

2. In a bending and forming brake, a stationary bed, clamping means mounted above said bed for clamping the work downwardly thereagainst, and a bending element pivoted adjacent the forward edge of the bed, and means for adjusting the axis of rotation of said bending element in relation to the forward upper edge of the bed, including a pair of arms located adjustably one at each side of a front portion of the bed, a pivotal connection between each said arm and the bending element, and means for adjusting each said arm in relation to said bed, including bolt and slot connections between each said arm and the bed.

3. In a bending and forming brake, a stationary bed, a generally triangular clamp, the base of the clamp being pivoted adjacent the rear of the bed, the apex of the clamp extending adjacent the front of the bed, a bending blade structure secured adjacent the apex of said clamp and located adjacent the forward edge of the bed, and means for exerting a clamping thrust

against said clamp adjacent its apex including a pressure bar extending transversely across the clamp adjacent its apex and in contact with the clamp adjacent the longitudinal axis of the clamp and means for locking the pressure bar in clamping position.

4. In a bending and forming brake, a stationary bed, a generally triangular clamp, the base of the clamp being pivoted adjacent the rear of the bed, the apex of the clamp extending adjacent the front of the bed, a bending blade structure secured adjacent the apex of said clamp and located adjacent the forward edge of the bed, and means for exerting a clamping thrust against said clamp adjacent its apex including a pressure bar extending transversely across the clamp, means for locking the pressure bar in clamping position and a contact element interposed between the clamp and the pressure bar.

5. In a bending and forming brake, a stationary bed, a generally triangular clamp, the base of the clamp being pivoted adjacent the rear of the bed, the apex of the clamp extending adjacent the front of the bed, a bending blade structure secured adjacent the apex of said clamp and located adjacent the forward edge of the bed, and means for exerting a clamping thrust against said clamp adjacent its apex including a pressure bar extending transversely across the clamp, means for locking the pressure bar in clamping position and a contact element interposed between the clamp and the pressure bar, the area of contact between said contact element and the pressure bar being located on a line perpendicular to the pivotal connection between the base of the clamp and the rear of the bed.

6. In a bending and forming brake, a stationary bed, a bending blade structure pivoted adjacent the forward edge of the bed, means for clamping the work downwardly against the bed, and means for applying downward compression against said clamping means, including an abutment vertically adjustable at one side of the bed, a clamping lever pivoted thereto and extending across the bed and above said clamping means, and means for depressing the opposite end of said clamping lever, including an actuating lever and a link pivoted to the free end of said clamping lever, and pivoted at its other end to said actuating lever, said actuating lever being pivoted in relation to the bed, the pivotal connection between the actuating lever and the bed being outside of a plane common to the axes of the pivotal connections between the link and the clamping lever and between the link and the actuating lever, whereby when the actuating lever is at the limit of its locking excursion, it is urged toward locking position by the resistance to the clamping lever of the work.

7. In a bending and forming brake, a stationary horizontal bed having a free forward working edge, a clamp structure rotatably mounted at its rear end in normally fixed relation to the bed and extending forwardly above the bed and adjacent said working edge, said clamp structure having at its forward end a blade receiving seat, means for securing a selected one of a plurality of clamp blades of different form to said seat, means for applying downward pressure against a forward portion of said clamp structure at an area intermediate the sides of the bed, and overlying the bed, and for thereby moving the clamp blade about the axis of the clamp structure, downwardly against the bed, and a

bending blade rotatably mounted adjacent the forward edge of the bed and means for rotating it upwardly against the work held by the clamp blade and for thereby upwardly bending the work.

5. In a bending and forming brake, a stationary horizontal bed having a free forward working edge, a clamp structure rotatably mounted at its rear end in normally fixed relation to the bed and extending forwardly above the bed and adjacent said working edge, said clamp structure having at its forward end a blade receiving seat, means for securing a selected one of a plurality of clamp blades of different form to said seat, means for applying downward pressure against a forward portion of said clamp structure at an area intermediate the sides of the bed, and overlying the bed, and for thereby moving the clamp blade about the axis of the clamp structure, downwardly against the bed, and a bending blade rotatably mounted adjacent the forward edge of the bed and means for rotating it upwardly against the work held by the clamp blade and for thereby upwardly bending the work, and means for adjusting the axis of rotation of said bending blade in relation to the bed.

9. In a bending and forming brake, a stationary horizontal bed having a free forward working edge, a clamp structure rotatably mounted at its rear end in normally fixed relation to the bed and extending forwardly above the bed and adjacent said working edge, said clamp structure having at its forward end a blade receiving seat, means for securing a selected one of a plurality of clamp blades of different form to said seat, means for applying downward pressure against a forward portion of said clamp structure at an area intermediate the sides of the bed, and overlying the bed, at a limited area located on a line perpendicular to the axis of rotation of the clamp structure and for thereby moving the clamp blade about the axis of the clamp structure, downwardly against the bed, and a bending blade rotatably mounted adjacent the forward edge of the bed and means for rotating it upwardly against the work held by the clamp blade and for thereby upwardly bending the work.

10. In a bending and forming brake, a stationary horizontal bed having a free forward working edge, a clamp structure rotatably mounted at its rear end in normally fixed relation to the bed and extending forwardly above the bed and adjacent said working edge, said clamp structure having at its forward end a blade receiving seat, means for securing a selected one of a plurality of clamp blades of different form to said seat, means for applying downward pressure against a forward portion of said clamp structure at an area intermediate the sides of the bed, and overlying the bed, at a limited area located on a line perpendicular to the axis of rotation of the clamp structure and for thereby moving the clamp blade about the axis of the clamp structure, downwardly against the bed, and a bending blade rotatably mounted adjacent the forward edge of the bed and means for rotating it upwardly against the work held by the clamp blade and for thereby upwardly bending the work, said means for applying downward pressure including a transversely extending clamp lever, a link connecting one end of said clamp lever with the bed, an operating lever pivoted at the opposite side of the bed and a link connecting the opposite end of said clamp

lever to said operating lever intermediate the ends of said operating lever.

11. In a bending and forming brake, a stationary horizontal bed having a free forward working edge, a clamp structure rotatably mounted at its rear end in normally fixed relation to the bed and extending forwardly above the bed and adjacent said working edge, said clamp structure having at its forward end a blade receiving seat, means for securing a selected one of a plurality of clamp blades of different form to said seat, means for applying downward pressure against a forward portion of said clamp structure at an area intermediate the sides of the bed, and overlying the bed, at a limited area located on a line perpendicular to the axis of rotation of the clamp structure and for thereby moving the clamp blade about the axis of the clamp structure, downwardly against the bed, and a bending blade rotatably mounted adjacent the forward edge of the bed and means for rotating it upwardly against the work held by the clamp blade and for thereby upwardly bending the work, said means for applying downward pressure including a transversely extending clamp lever, a link connecting one end of said clamp lever with the bed, an operating lever pivoted at the opposite side of the bed, a link connecting the opposite end of said clamp lever to said operating lever intermediate the ends of said operating lever and a pedal associated with said brake and an actuating connection between said pedal and said operating lever.

12. In a bending and forming brake, a stationary horizontal bed having a free forward working edge, a clamp structure rotatably mounted at its rear end in normally fixed relation to the bed and extending forwardly above the bed and adjacent said working edge, said clamp structure having at its forward end a blade receiving seat, means for securing a selected one of a plurality of clamp blades of different form to said seat, means for applying downward pressure against a forward portion of said clamp structure at an area intermediate the sides of the bed, and overlying the bed and for thereby moving the clamp blade about the axis of the clamp structure downwardly against the bed, and a bending blade rotatably mounted adjacent the forward edge of the bed and means for rotating it upwardly against the work held by the clamp blade and for thereby upwardly bending the work, and means for adjusting the axis of rotation of said clamp structure in relation to said bed.

13. In a bending and forming brake, a stationary horizontal bed having a free forward working edge, a clamp structure rotatably mounted at its rear end in normally fixed relation to the bed and extending forwardly above the bed and adjacent said working edge, said clamp structure having at its forward end a blade receiving seat, means for securing a selected one of a plurality of clamp blades of different form to said seat, means for applying downward pressure against a forward portion of said clamp structure at an area intermediate the sides of the bed, and overlying the bed and for thereby moving the clamp blade about the axis of the clamp structure downwardly against the bed, and a bending blade rotatably mounted adjacent the forward edge of the bed and means for rotating it upwardly against the work held by the clamp blade and for thereby upwardly bending the work, and abutment means for the work, ad-

justable on said bed toward and away from said forward working edge.

14. In a bending and forming brake, a stationary horizontal bed having a free forward working edge, a clamp structure rotatably mounted at its rear end in normally fixed relation to the bed and extending forwardly above the bed and adjacent said working edge, said clamp structure having at its forward end a blade receiving seat, means for securing a selected one of a plurality of clamp blades of different form to said seat, means for applying downward pressure against a forward portion of said clamp structure at an area intermediate the sides of the bed, and overlying the bed and for thereby moving the clamp blade about the axis of the clamp structure downwardly against the bed, and a bending blade rotatably mounted adjacent the forward edge of the bed and means for rotating it upwardly against the work held by the clamp blade and for thereby upwardly bending the work, and means for adjusting the edge of said bending blade toward and away from its axis of rotation.

15. In a bending and forming brake, a stationary horizontal bed having a free forward working edge, a clamp structure rotatably mounted at its rear end in normally fixed relation to the bed and extending forwardly above the bed and adjacent said working edge, said clamp structure having at its forward end a blade receiving seat, means for securing a selected one of a plurality of clamp blades of different form to said seat, means for applying downward pressure against a forward portion of said clamp structure at an area intermediate the sides of the bed, and overlying the bed and for thereby moving the clamp blade about the axis of the clamp structure downwardly against the bed, and a bending blade support rotatably mounted adjacent the forward edge of the bed, means for rotating it upwardly toward the work held by the clamp blade, and a bending blade adjustably mounted on said support.

16. In a bending and forming brake, a stationary horizontal bed having a free forward working edge, a clamp structure rotatably mounted at its rear end in normally fixed relation to the bed and extending forwardly above the bed and adjacent said working edge, said clamp structure having at its forward end a blade receiving seat, means for securing a selected one of a plurality of clamp blades of different form to said seat, means for applying downward pressure against a forward portion of said clamp structure at an area intermediate the sides of the bed, and overlying the bed and for thereby moving the clamp blade about the axis of the clamp structure downwardly against the bed, and a bending blade support rotatably mounted adjacent the forward edge of the bed, means for rotating it upwardly toward the work held by the clamp blade, and a bending blade adjustably mounted on said support and means for adjusting the axis of rotation of said bending blade support in relation to the bed.

17. In a bending and forming brake, a stationary bed having a free forward edge, said bed having a length of the order of its width, a generally triangular clamp, the base of the clamp being pivoted adjacent the rear of the bed, the apex of the clamp extending adjacent the front of the bed, a bending blade structure secured adjacent the apex of said clamp and located adjacent the forward edge of the bed, and means for exerting a clamping thrust against said clamp adjacent its apex, including a localized upward

extension from the clamp, and lever means for engaging said extension and for exerting a downward thrust thereagainst.

18. In a bending brake structure, a bed having a free forward edge readily accessible to an operator from in front of the bed, said bed having a length of the order of its width, a clamp frame, of the same general length as the bed, pivoted to said bed adjacent the rear end of the bed, a clamp blade removably secured to the forward end of said clamp frame, and overlying the bed adjacent said free edge, means for directing a downward clamping pressure against said frame at a localized point generally midway of the width of the frame and nearer to the front than the rear of the bed, gauging means longitudinally adjustable on said bed, and bending means pivotally mounted adjacent the forward edge of said bed.

19. In a bending brake structure, a bed having a free forward edge readily accessible to an operator from in front of the bed, said bed having a length of the order of its width, a clamp frame, of the same general length as the bed, pivoted to said bed adjacent the rear end of the bed, a clamp blade removably secured to the forward end of said clamp frame, and overlying the bed adjacent said free edge, means for directing a downward clamping pressure against said frame at a localized point generally midway of the width of the frame and nearer to the front than the rear of the bed, gauging means longitudinally adjustable on said bed, and bending means pivotally mounted adjacent the forward edge of said bed, said clamping pressure means including a clamping lever extending transversely across said bed above said frame, the opposed parts of clamping lever and frame being formed and adapted to maintain contact over a limited area, one end of said clamping lever being pivoted to the bed, and an actuating lever, for said clamping lever, pivoted to said bed, and connected to the free end of said clamping lever.

20. In a bending and forming brake, a stationary bed, a generally triangular clamp, the base of the clamp being pivoted adjacent the rear of the bed, the apex of the clamp extending adjacent the front of the bed, a bending blade structure secured adjacent the apex of said clamp and located adjacent the forward edge of the bed, and means for exerting a clamping thrust against said clamp adjacent its apex including a pressure bar extending transversely across the clamp adjacent its apex and in contact with the clamp adjacent the longitudinal axis of the clamp and means for locking the pressure bar in clamping position, and means for bending upwardly any work which is gripped between the bending blade structure and the stationary bed.

21. In a bending and forming brake, a stationary bed, a generally triangular clamp, the base of the clamp being pivoted adjacent the rear of the bed, the apex of the clamp extending adjacent the front of the bed, a bending blade structure secured adjacent the apex of said clamp and located adjacent the forward edge of the bed, and means for exerting a clamping thrust against said clamp adjacent its apex including a pressure bar extending transversely across the clamp, means for locking the pressure bar in clamping position and a contact element interposed between the clamp and the pressure bar and means for bending upwardly any work which is gripped between the bending blade structure and the stationary bed.

22. In a bending and forming brake, a stationary bed, a generally triangular clamp, the base of the clamp being pivoted adjacent the rear of the bed, the apex of the clamp extending adjacent the front of the bed, a bending blade structure secured adjacent the apex of said clamp and located adjacent the forward edge of the bed, and means for exerting a clamping thrust against said clamp adjacent its apex including a pressure bar extending transversely across the clamp, means for locking the pressure bar in clamping position and a contact element interposed between the clamp and the pressure bar, the area of contact between said contact element and the pressure bar being located on a line perpendicular to the pivotal connection between the base of the clamp and the rear of the bed, and means for bending upwardly any work which is gripped between the bending blade structure and the stationary bed.

PETER KILHAM.
